ABSTRACT OF THE DISCLOSURE

Paraffinic and/or alkyl substituted aromatic hydrocarbons are isomerized with a catalyst comprising (a) a Lewis acid of the formula MX_n where M is selected from Group IV-B, V or VI-B of the Periodic Table, X is a halogen and n varies from 3 to 6, and (b) a strong Bronsted acid comprising fluorosulfuric acid, trifluoromethanesulfonic acid, trifluoroacetic acid or mixtures thereof.

BACKGROUND OF THE INVENTION

The present invention relates to a process for isomerizing paraffins and/or alkyl substituted aromatic hydrocarbons. More particularly, the invention relates to the isomerization of branched and straight chain aliphatic and cycloaliphatic hydrocarbons and/or alkyl substituted aromatic hydrocarbons at isomerization conditions in the presence of a strong acid catalyst. Still more particularly, the invention relates to the isomerization of C_4 to C_{20} paraffins and alkyl substituted aromatic hydrocarbons in the presence of a catalyst comprising a Lewis acid and a strong Bronsted acid.

DESCRIPTION OF THE PRIOR ART

It is well known that the more highly branched isomers of the paraffinic hydrocarbons occurring in petroleum oil gasoline fractions are more valuable than the corresponding slightly branched or straight chain hydrocarbons due to their higher octane ratings. The demand for gasolines with high octane numbers has been due chiefly to the production of gasoline engines with increasingly higher compression ratios. One of the economically important ways in which the increased demands for high octane fuels can be met is through the isomerization of light naphtha components of such fuels.

The isomerization of aliphatic, cycloaliphatic and alkyl aromatic hydrocarbons is well known. It is customary to employ certain Lewis acids, particularly aluminum chloride or aluminum bromide, in conjunction with certain promoters, such as hydrogen chloride, hydrogen bromide or hydrogen fluoride as isomerization catalysts. Thus, for example, Canadian Pats. 742,746 and 794,400 disclose the use of antimony pentafluoride/hydrogen fluoride in solution or on a solid support as an isomerization catalyst.

Insofar as the isomerization of light naphthas is concerned, the lower the temperature of isomerization, the more favorable is the equilibrium for converting straight chain paraffin hydrocarbons into branched chain isomers. One of the problems with the known catalyst systems is the relatively high temperatures that must be employed for the isomerization process. This may lead to increased cracking and disproportionation and, thus, a reduced yield of branched chain hydrocarbon. Another problem is the frequently high volatility of the catalyst system, necessitating pressurized reactor systems. It has now been found that these problems can be circumvented by use of the special acid catalyst systems of this invention.

SUMMARY OF THE INVENTION

In accordance with this invention, isomerizable hydrocarbons selected from the group consisting of paraffins,

2

alkyl substituted aromatic hydrocarbons and mixtures thereof, containing, preferably, 4 to 20 carbon atoms per molecule are isomerized at low temperatures in the presence of a catalyst comprising (a) one or more Lewis acids of the formula MX_n where M is selected from Group IV-B, Group V or Group VI-B elements of the Periodic Table, X is a halogen, preferably fluorine, and n varies from 3 to 6, and (b) a strong Bronsted acid, preferably comprising a strong halogen-substituted acid such as fluorosulfuric acid, trifluoromethanesulfonic acid, trifluoroacetic acid or mixtures thereof. The Periodic Table referred to is that described in "The Encyclopedia of Chemistry," Reinhold Publishing Corporation, 2nd ed. (1966) at p. 790. The term "elements" as used herein refers to the metals and metalloids of the aforementioned groups of the Periodic Table.

Specific examples of useful Lewis acids include antimony pentafluoride, arsenic pentafluoride, tantalum pentafluoride, niobium pentafluoride, vanadium pentafluoride, titanium tetrafluoride, bismuth pentafluoride, phosphorus pentafluoride, molybdenum hexafluoride, zirconium tetrafluoride, mixtures thereof and the like. Moreover, chlorine, bromine or iodine may be substituted for fluorine without affecting the efficiency of the catalyst system.

Preferably, the catalyst composition will comprise only one Lewis acid and one Bronsted acid. Exemplary of such catalyst compositions that are encompassed by this invention are the following.

Catalyst No.:

- 1 ____ Antimony pentafluoride-fluorosulfuric acid.
- 2 ____ Arsenic pentafluoride-fluorosulfuric acid.
- 3 ____ Tantalum pentafluoride-fluorosulfuric acid.
- 4 ____ Niobium pentafluoride-fluorosulfuric acid.
- 5 ____ Vanadium pentafluoride-fluorosulfuric acid.
- 6 ____ Titanium tetrafluoride-fluorosulfuric acid.
- 7 ____ Molybdenum hexafluoride-fluorosulfuric acid.
- 8 ____ Antimony pentafluoride-chlorosulfuric acid.
- 9 ____ Antimony pentafluoride-trifluoromethane-sulfonic acid.
- 10 ____ Arsenic pentafluoride-trifluoromethane-sulfonic acid.
- 11 ____ Tantalum pentafluoride-trifluoromethane-sulfonic acid.
- 12 ____ Niobium pentafluoride-trifluoromethane-sulfonic acid.
- 13 ____ Vanadium pentafluoride-trifluoromethane-sulfonic acid.
- 14 ____ Titanium tetrafluoride-trifluoromethane-sulfonic acid.
- 15 ____ Molybdenum hexafluoride-trifluoromethane-sulfonic acid.
- 16 ____ Zirconium tetrafluoride-trifluoromethane-sulfonic acid.
- 17 ____ Antimony pentafluoride-trifluoroacetic acid.
- 18 ____ Tantalum pentafluoride-trifluoroacetic acid.
- 19 ____ Arsenic pentafluoride-trifluoroacetic acid.
- 20 ____ Titanium tetrafluoride-trifluoroacetic acid.
- 21 ____ Zirconium tetrafluoride-trifluoroacetic acid.
- 22 ____ Vanadium pentafluoride-trifluoroacetic acid.
- 23 ____ Molybdenum hexafluoride-trifluoroacetic acid.
- 24 ____ Niobium pentafluoride-trifluoroacetic acid.

The molar ratio of Brønsted acid to Lewis acid can range from about 20:1 to 1:5. Preferably, a 5:1 to 1:1 molar ratio is employed. The amount of the catalyst system present in the isomerization zone with reference to the total amount of hydrocarbon present therein can range from about 0.01 to 100 parts or even higher by weight of the catalyst composition per part by weight of hydrocarbon. Preferably, the amount of catalyst present in the zone can range from 1 to 10 parts by weight of the catalyst composition per part by weight of the hydrocarbon.

The catalyst may be used as the neat liquid, as a

The catalyst may be used as the neat liquid, as a diluted solution or adsorbed on a solid support. With regard to the diluted catalyst, any diluent may be used that is inert under the reaction conditions. To obtain optimum results, the diluents should be pretreated to remove catalyst poisons such as water, unsaturated compounds and the like. Typical diluents include sulfonyl chloride fluoride, sulfonyl fluoride, fluorinated hydrocarbons and mixtures thereof. Protic acids including fluorosulfuric acid, sulfuric acid, trifluoromethanesulfonic acid and the like, themselves, can be used as diluents. The diluent:catalyst volume ratio can range from about 50:1 to 1:1 and, preferably, from 10:1 to 2:1.

The catalyst system may be employed incorporated with a suitable solid carrier or support. Any solid catalyst support may be used that is substantially inert to the catalyst under the reaction conditions. The support should be pretreated, such as by heating, chemical treatment or coating, to remove substantially all water and/or hydroxyl groups that might be present. Active supports may be rendered inert by coating them with an inert material such as antimony trifluoride or aluminum trifluoride. Suitable solid supports include fluoride-treated or coated resins such as sulfonated cation exchange resins, fluoride-treated acidic chalcides such as alumina and aluminosilicates, and acid-resistant molecular sieves such as a zeolite, e.g., faujasite. The supported catalysts can be prepared in any suitable manner, such as by conventional methods including dry mixing, coprecipitation or impregnation. In one embodiment, the supported catalyst is prepared by impregnating a suitable deactivated support with a metal fluoride such as antimony pentafluoride and then with a Bronsted acid such as fluorosulfuric acid.

The weight ratio of the Lewis acid to the support may range from 1:100 to 1:10 and preferably, from 1:50 to 1:35. The weight ratio of the Brønsted acid to the support may range from 1:100 to 1:10 and, preferably, from 1:50 to 1:35.

Feedstocks that may be used in the instant process include paraffins, alkyl substituted aromatic hydrocarbons and mixtures thereof. The paraffins as herein defined include aliphatic and cycloaliphatic hydrocarbons that are substantially in the liquid phase at room temperature. The aliphatic hydrocarbons (straight and branched chain materials) can contain 4 to 20 carbon atoms per molecule, preferably 4 to 8 carbon atoms, and may be exemplified by n-butane, n-pentane, methylpentane, methylhexane and the like. The cycloaliphatic hydrocarbons (naphthenes) can contain 6 to 20 carbon atoms per molecule, preferably 6-12 carbon atoms, and may be exemplified by methylcyclopentane, the dimethylcyclopentanes, ethylcyclohexane, n-pentylcyclohexane and the like. Depending on reaction conditions, isomerization of the ring, i.e. ring expansion or contraction, may compete with side chain isomerization. The alkyl substituted aromatic hydrocarbons can contain 7 to 20 carbon atoms per molecule, preferably 7 to 12 carbon atoms, and may include in principle all isomerizable alkylaromatic or polyalkylaromatic hydrocarbons such as the xylenes, n-butyl benzene and the like. Both positional isomerization of the alkyl groups substituted on the ring and side chain isomerization may occur depending on reaction conditions. Other aliphatic or alicyclic hydrocarbons commonly found in

conventional petroleum hydrocarbon light naphtha streams may also be present.

The feed may contain various cracking inhibitors or moderators such as hydrogen and the like. The inhibitors act to depress excessive cleavage reactions that may occur during the isomerization. When hydrogen is used, it is employed in amounts ranging, preferably, from 1 to 3 mole percent based on hydrocarbon feed.

The process catalyst system is somewhat sensitive to impurities such as water; therefore, the alkylation should be conducted substantially, in the absence of large amounts of moisture, i.e. by the use of anhydrous reagents, by purification of the starting reagents, etc.

The process of the invention is conducted as a batch or continuous type operation. In general, the various means customarily employed in extraction processes to increase the contact area between the hydrocarbon phase and the catalyst phase may be used. In one embodiment of the invention, the hydrocarbon phase and catalyst phase may be contacted substantially in the liquid phase. The apparatus employed may be of a conventional nature and may comprise a single reactor such as a fluidized-bed reactor or multiple reactors equipped with efficient stirring devices, such as mechanical agitators, jets of restricted internal diameter, turbo mixers, etc. The hydrocarbon phase and the catalyst phase may be passed through one or more reactors in concurrent, cross-current or counter-current flow. Unreacted reactants, catalysts, inhibitors, and heavier products of the reaction may be separated from the desired isomeric product and from one another such as by distillation and returned in whole or in part to the isomerization zone. The resultant product may be further processed as by alkylation and the like, or be employed directly as a high octane gasoline blending agent.

The reaction temperatures for the isomerization can vary in the range of about -30° to 100° C., using liquid catalysts, and preferably 20 to 60° C. When using supported solid acid catalysts, temperatures can range from about +20 to 350° C., preferably 50 to 200° C. The reaction pressure can range from about 1 atmosphere to 50 atmospheres and preferably from 1 atmosphere to 20 atmospheres. The hydrocarbon feed can be in either the liquid or gaseous phase and is preferably predominantly in the liquid phase.

The contact time of the catalyst and hydrocarbon is subject to wide variation, being dependent in part upon the temperature and catalyst concentrations employed. In general, for liquid phase systems, contact times between 0.1 and 10 hours, usually 0.2 to 5 hours, may be employed.

BRIEF DESCRIPTION OF THE DRAWING

The drawing is a flow diagram of a preferred embodiment of the invention. In this connection, the invention will be particularly described with reference to the isomerization of n-hexane in the presence of an antimony pentafluoride/trifluoromethanesulfonic acid catalyst system.

Referring now to the drawing in detail, n-hexane is introduced into isomerization zone 2, in the liquid phase, from a source, not shown, by way of line 1. An equimolar mixture of antimony pentafluoride and trifluoromethane sulfonic acid is introduced into zone 2 via line 3. The amount of catalyst charged is 20 g. per 100 g. of n-hexane. The temperature within the isomerization zone is maintained between the range of 20 to 25° C. while the pressure is maintained at 1 atmosphere. The isomerization zone is provided with an agitator to ensure thorough contacting of the reactants. The contacting time is about 2-6 hours.

The isomerized product is discharged from zone 2 via line 4 and sent to settling zone 5. Upon standing for a period of time, the product separates into a hydrocarbon phase and an inorganic phase containing the acid catalyst that is essentially insoluble in the hydrocarbon phase. The separated acid catalyst is then withdrawn from zone 5

and recycled to the isomerization zone 2 via line 6 for reuse. The separated hydrocarbon phase is discharged from settling zone 5 via line 7 and contacted therein with caustic (e.g. about 20% by weight sodium hydroxide) introduced via line 8. The amount of caustic added thereto is 10 gms. per 100 gms. of n-hexane. The n-hexane/caustic mixture is introduced into mixing zone 9 and intimately mixed therein. The mixture is then withdrawn from the mixing zone by means of line 10 and introduced into settling zone 11, wherein the caustic phase separates from the hydrocarbon phase.

The caustic phase is removed via line 12 and the hydrocarbon phase is removed via line 13 and introduced into a separation zone 14 illustrated as a distillation zone that is provided with a heating means such as steam coil 15 and with lines 16, 17, 18, 19 and 20. Conditions of temperature and pressure are adjusted in zone 14 to recover the product either in one fraction (line 16) or in several fractions by lines 17 and 18 while unreacted n-hexane feed may be discharged by line 19 and preferably recycled to isomerization zone 2 via lines 19 and 1. The heavy side products are discharged from the separation zone 14 by line 20.

The invention will be further understood by reference to the following examples that include a preferred embodiment of the invention.

DESCRIPTION OF THE PREFERRED EMBODIMENT

Example 1

Several isomerization reactions were performed in a batchwise manner using a 500 cubic centimeter tetra-fluoroethylene polymer (Teflon®)-lined stainless-steel reactor, equipped with a stirring device. Normal hexane was used as the hydrocarbon feedstock. Reaction conditions and product distributions are given in the following table.

Product analysis

Table I summarizes isomerization product compositions as determined by gas-liquid chromatography using a 150 foot, 0.01 inch I.D. squalene column and a hydrogen ionization flame detector.

¹ Catalyst consists of equimolar proportions of metal fluoride and Bronsted acid.

It will be noted from Table I that product of high C₆⁺ content can be prepared by use of the catalysts of this invention. Moreover, low reaction temperatures can be used to carry out the reactions vis-a-vis sulfuric acid

based isomerizations, thus minimizing complications arising from competitive side reactions.

What is claimed is:

1. A process for the isomerization of isomerizable hydrocarbons selected from the group consisting of paraffins, alkyl substituted aromatic hydrocarbons and mixtures thereof comprising contacting said isomerizable hydrocarbon at isomerization conditions with a catalyst comprising (a) a Lewis acid of the formula MX_n where M is selected from the Group V elements of the Periodic Table, X is a halogen and n varies from 3 to 6, and (b) a Bronsted acid comprising fluorosulfuric acid, said contacting occurring substantially in the liquid phase.

2. The process of claim 1 wherein said paraffins contain 4 to 20 carbon atoms per molecule and are selected from the group consisting of aliphatic and cycloaliphatic hydrocarbons and where said alkyl substituted aromatic hydrocarbons contain 7 to 20 carbon atoms per molecule.

3. The process of claim 1 wherein the Lewis acid is selected from the group consisting of antimony pentafluoride, tantalum pentafluoride, niobium pentafluoride, vanadium pentafluoride, bismuth pentafluoride, arsenic pentafluoride, and phosphorus pentafluoride.

4. The process of claim 1 wherein said catalyst consists of niobium pentafluoride and fluorosulfuric acid.

5. The process of claim 1 wherein said catalyst consists of antimony pentafluoride and fluorosulfuric acid.

6. The process of claim 1 wherein said catalyst consists of tantalum pentafluoride and fluorosulfuric acid.

7. The process of claim 1 wherein the catalyst and hydrocarbon are contacted in the presence of an inert diluent.

8. The process of claim 7 wherein said diluent is selected from the group consisting of sulfonyl chloride fluoride, sulfonyl fluoride and fluorinated hydrocarbons.

9. A catalytic isomerization process comprising contacting isomerizable hydrocarbons selected from the group consisting of C₄ to C₁₂ paraffins, C₇ to C₂₀ alkyl substituted aromatic hydrocarbons and mixtures thereof, at isomerization conditions with a catalyst comprising (a) a metal fluoride wherein the metal is selected from the group consisting of titanium and Group V and Group

VI-B metals of the Periodic Table, and (b) a Bronsted acid selected from the group consisting of fluorosulfuric acid, trifluoromethanesulfonic acid and trifluoroacetic acid wherein said contacting occurs substantially in the

liquid phase and at a temperature between about -30 and 100° C. and at a pressure between the range of about 1 atmosphere and 50 atmospheres.

10. The process of claim 9 wherein said catalyst comprises tantalum pentafluoride and fluorosulfuric acid.

11. A process for the isomerization of isomerizable hydrocarbons selected from the group consisting of paraffins, alkyl substituted aromatic hydrocarbons and mixtures thereof comprising contacting said isomerizable hydrocarbons at isomerization conditions with a catalyst comprising (a) a Lewis acid of the formula MX_n where M is selected from the group consisting of titanium and Group V and Group VI-B elements of the Periodic Table, X is a halogen and n varies from 3 to 6, and (b) a Bronsted acid selected from the group consisting of trifluoromethanesulfonic acid and trifluoroacetic acid.

12. The process of claim 11 wherein said catalyst consists of antimony pentafluoride and trifluoromethanesulfonic acid.

13. The process of claim 11 wherein said catalyst consists of tantalum pentafluoride and trifluoromethanesulfonic acid.

14. The process of claim 11 wherein the catalyst is supported on a solid carrier that is substantially inert to the supported acid.

15. A process for the isomerization of an isomerizable hydrocarbon selected from the group consisting of paraffins, alkyl substituted aromatic hydrocarbons and mixtures thereof comprising contacting said isomerizable hydrocarbons at isomerization conditions with a catalyst comprising (a) a Lewis acid of the formula MX_n where M is selected from the group consisting of titanium and Group V and Group VI-B elements of the Periodic Table, X is a halogen and n varies from 3 to 6, and (b) fluorosulfuric acid, where said fluorosulfuric acid and

Lewis acid are supported on a solid carrier that is substantially inert to said supported acids, said solid carrier selected from the group consisting of fluoride-treated resins, fluoride-treated acidic halides and acid-resistant molecular sieves.

10 16. A process for the isomerization of isomerizable hydrocarbons selected from the group consisting of paraffins, alkyl substituted aromatic hydrocarbons and mixtures thereof comprising contacting said isomerizable hydrocarbons at isomerization conditions with a catalyst comprising (a) a Lewis acid of the formula MX_n where M is selected from the group consisting of titanium and Group VI-B elements of the Periodic Table, X is a halogen and n varies from 3 to 6, and (b) a Bronsted acid comprising fluorosulfuric acid.

15 17. In a process for the isomerization of an isomerizable hydrocarbon selected from the group consisting of paraffins, alkyl substituted aromatic hydrocarbons and mixtures thereof, the step of contacting said isomerizable hydrocarbon at isomerization conditions with a catalyst comprising antimony pentafluoride and trifluoroacetic acid.
